UNITED STATES PATENT OFFICE

JOHN A. CHILSTROM, OF RED WING, MINNESOTA.

DISPLAY-CABINET.

1,267,377.

Specification of Letters Patent. Patented May 28, 1918.

Application filed April 12, 1917. Serial No. 161,610.

To all whom it may concern:

Be it known that I, JOHN A. CHILSTROM, a citizen of the United States, residing at Red Wing, in the county of Goodhue and State of Minnesota, have invented a new and useful Display-Cabinet, of which the following is a specification.

My invention relates to cabinets for the display of merchandise, and the main object 10 is to provide a convenient and efficient cabinet for the display of package seed, that is, seed sold in envelopes or similar packages. A further object is to so construct such cabinet that it will hold also a stock of seed packages beside the smaller stock displayed; 15 and to make such cabinet foldable for storing and shipping.

In the accompanying drawing:

Figure 1 is an elevation of either side of 20 my improved cabinet set up for use. Fig. 2 is a bottom view of the cabinet with its legs in folded position. Fig. 3 is a side view of the cabinet on a reduced scale and knocked down for shipping. Fig. 4 is a 25 cross section on the line *a—a* of Fig. 1. Fig. 5 is a section on the line *b—b* Fig. 2 with the legs in open position. Fig. 6 is a perspective view of one of the main partitions in the displaying portion of the cabinet. Fig. 7 is a perspective view of one of 30 the smaller partitions inserted between the main partitions like Fig. 6.

Referring to the drawing by reference numerals. 1 designates the horizontal main 35 frame or body of the cabinet, which frame to save material has its inside made up of flat bars 2 and 3. In the four corners of the hollow underside of the frame are pivoted at 4 four legs 5, which may be folded 40 into the cavity of the frame in the positions shown in Fig. 2. Each leg has its lower end provided with a cavity 6, in which when the leg is folded, engages a spring catch 7, which is secured to the frame at 8 and ex- 45 tends with its other end as a spring arm 9, which when the leg is set up holds it firmly against the vertical side or end portion of the frame. When the leg is to be folded said arm 9 is simply pressed upward until 50 the leg can fold and be held folded by the catch 7.

Slidable upon the bars 3 are two oppo-

sitely arranged drawers 10 with pulls 11; and upon the bars are normally resting, as shown in dotted lines in Fig. 4, two trays 55 12, each of which is divided into cells 13 by vertical fixed partitions 14 having vertical side grooves 15 for the edges 16 of thinner partitions 17 to be pushed or dropped down into. Said partitions 17 are preferably 60 made of sheet metal and formed at the lower end with a horizontal portion 18. To bring the cells into vertical position as shown in Fig. 4, the trays 12 are raised with their adjacent edges or sides 12^a inclined in 65 opposite directions, as shown in Fig. 4; and to hold them in said position, a wedge shaped strip 19 is placed between them and retained by having one or more catches 20 engaging under the adjacent bottom edges of the trays. 70 In said strip or wedge 19 is fixed a sign board 21, upon the sides of which is painted or printed words to indicate the general contents of the tray, for instance "Seeds"; and in the various cells are placed in vertical positions packages containing seeds, the names of which are printed across the end of the package or envelop displayed above the cells, so that the merchant and customers may readily find the kind of seed wanted, as for instance, "Carrots," "Beets," 80 "Peas," "Turnips," etc.

The stock of seed for some time not displayed may be kept in the drawers 10, and also on a large shelf 22, which has its edges 85 supported in notches 23 in the legs 5. Said shelf also aids to make the cabinet stand firmly; and when the cabinet is to be knocked down for shipping or storing, the wedge 19 is removed from its place, the 90 trays lowered to parallel position with the top of the frame and the latter closed by placing upon it the shelf 22 as a cover which is secured by screws 24, as shown in Fig. 3, where also the legs are shown folded and 95 the cabinet ready for shipping. In Fig. 2 the diagonal dotted lines 19—21 indicate how during shipping the wedge 19 and sign board 21 may be placed in the space between the folded legs 5. To accomplish this more 100 conveniently the wedge and the board may be made somewhat narrower than shown, or the downward rails of the frame may be made deeper than shown.

What I claim is:

1. In a cabinet of the class described, a horizontally disposed hollow frame, a pair of trays placed in the upper part of the frame and divided into pockets for holding goods to be partly exposed above the pockets, a wedge-shaped member interposed between the adjacent edges of the two trays

to hold the trays inclined one of them away from each side of the wedge.

2. The structure set forth in claim 1, in which the wedge-shaped member is detachable to allow the tray to occupy a horizontal position in the frame.

In testimony whereof I affix my signature.

JOHN A. CHILSTROM.
